UNITED STATES PATENT OFFICE.

ROBERT BEVERLY OGDEN, OF REDLANDS, CALIFORNIA.

DOOR-HOLDER.

1,036,890.

Specification of Letters Patent. Patented Aug. 27, 1912.

Application filed March 20, 1911. Serial No. 615,780.

To all whom it may concern:

Be it known that I, ROBERT B. OGDEN, a citizen of the United States, residing at Redlands, in the county of San Bernardino 5 and State of California, have invented a new and useful Door-Holder, of which the following is a specification.

This invention relates to door fastening devices which may be placed under a door 10 for the purpose of holding the door in a convenient angle while performing work on the door, such as adjusting locks or dressing the door for the purpose of fitting or finishing the door, and one of the main objects of the 15 invention is to produce a device of the character described, of simple construction which may be readily placed in position for holding the door for the purpose of securing and holding the same.

Another object of the invention is to produce a device of the character described 20 which may be placed under doors having varying degrees of clearance from the floor.

Other objects and advantages will appear 25 hereinafter from the following description.

Referring to the drawings which are for 30 illustrative purposes only: Figure 1 is a perspective view of a device embodying a form of my invention, showing the holder 35 under the lower free corner of the door. Fig. 2 is a vertical sectional view taken through the center of the device showing a portion of the door in dotted lines. Fig. 3 is a sectional view on line x^3-x^3 Fig. 2, 40 showing a portion of the door thereon. Fig. 4 is a vertical sectional view similar to Fig. 2, showing the position of the parts of the device when applied to a door having less clearance from the floor than that shown in Figs. 1, 2 and 3. Fig. 5 is a horizontal sectional view on line x^5-x^5 Fig. 2.

The device as shown, consists of a floor member or supporting member 1 of sheet metal having a base 2, adapted to rest on the floor and terminating at each side in upturned portions or standards 3, each having on its inner face a rib 4. Slidable vertically between the two standards 3 of the supporting member 1 is a U-shaped clamping member or stirrup 5 having two side arms 6 and a central portion 7. Each side arm 6 of the stirrup adjacent to the central portion 7 is provided with a pair of outward projections or lugs 9 which engage the ribs 4 on the standards 3, and each side arm 6 near the upper end thereof is perforated to receive a

bolt 8 which extends through a slot 19 in the adjacent standard 3. The heads of the bolts 8 abut against the inner faces of the arms 6 and are each provided with a washer 60 10 and nut 11 on the outside of the adjacent standard 3. The lugs 9 in engagement with the ribs 4 on the standards 3 and the bolts 8 in engagement with the slots 19 in the standards 3 prevent lateral movement of 65 the stirrup in the supporting member 1, but permit free vertical movement of the stirrup therein.

Pivots mounted on the bolts 8 between each of the standards 3 and the adjacent arm 6 of the stirrup 5 is a cam member 12 consisting of a sheet metal plate having a series of cam faces 13 arranged at varying distances from the pivot or bolt 8, which cam faces 13 are arranged to engage the upper 70 edge of a head 14 formed on the upper end of the ribs 4 on the standards 3 of the stationary member 1. The two cam members 12 terminate in arms 15 extending downwardly therefrom, joined at their lower ends 75 by a cross-piece or connecting member 16. The cross-piece 16 serves as an operating means for the cam members 12 and is provided in its central portion with a rib 17 for the purpose of giving additional 80 strength to the same.

The upper face of the central portion 7 of the stirrup 5 is provided with a series of 85 projections which are adapted to bite into the wood of the door and thereby prevent any slipping of the door holder.

Each of the heads 14 projects into a vertical slot 6' in the adjacent arms 6 of the stirrup 5 for the purpose of limiting the vertical sliding movement of the stirrup, the 90 slots 6' being long enough to permit the central portion 7 of the stirrup to enter an opening 2' in the base of the floor member 1 when it is desired to place the holder under a door having very little clearance from the 100 floor.

The device is operated in the following manner: The cam members 12 are turned so that the stirrup 5 is lowered sufficiently to permit the stirrup to be inserted under the 105 outer free corner of the door 20, and when in such position the cam members 12 are turned by pressing against the operating member 16 with the foot until the one of the cam faces 13, which is the required distance away from the bolt 8 to cause a clamping action between the central 110

portion 7 of the stirrup and the bottom of the door, is brought into engagement with the adjacent head 14. It will be noted that in the position shown in Figs. 1, 2 and 3, 5 the cam members 12 have been turned so that one of the cam faces 13 farthest from the pivot 8 is brought into contact relation with the head 14 in which case the stirrup 5 is raised a considerable distance from the 10 floor to accommodate the stirrup to a door having a very large margin of clearance above the floor. In the position of the parts shown in Fig. 4, one of the cam faces 13 nearer to the pivot than that in operation 15 in Figs. 1, 2 and 3, is brought into play, thus permitting the stirrup 5 to bind against the bottom of a door which has less clearance than the door illustrated in Figs. 1, 2 and 3. If the door to be worked upon 20 has but very little clearance as is illustrated in dotted lines in Fig. 4, the cam member 12 would be turned so that the cam face 13' would be brought into engagement with the head 14 on the supporting member 1, 25 and in such position the stirrup 5 would assume the position shown in dotted lines which would clamp against the underside of the door and hold the same rigidly in place while the door is being worked upon. 30 The cam portions 13 being arranged on both sides of the arms 15 provide for maximum adjustability of the stirrup. Thus when the device is adjusted, as shown in Fig. 2, the stirrup is adjusted for a door

the lower edge of which is relatively high, 35 while when in the position shown in Fig. 4, it is adjusted for a door the lower edge of which is relatively low. Any intermediate clamping position is provided by the intermediate cam portions. 40

What I claim is:

A door holder comprising a U-shaped floor member, a stirrup slideable in the floor member and adapted to support the lower edge of the door, a U-shaped cam member, 45 each arm of which is provided with a cam at the end thereof and extending around on each side of said arm, each cam portion being pivoted to the adjacent arm of the stirrup, the cam portion on one side of the pivot 50 of each cam being closer to said pivot than the cam portion on the other side, whereby when the cam member is swung into a position on one side of the stirrup the stirrup will be lifted to the highest point and when 55 the cam member is swung into a position on the other side of the stirrup the stirrup will be adjusted to its lowest clamping point, and abutments on the floor member against 60 which the said cams bear.

In testimony whereof, I have hereunto set my hand at Redlands, California, this 13th day of March, 1911.

ROBERT BEVERLY OGDEN.

In presence of—

G. T. HACKLEY,
JOSEPH OGDEN.
